MATERIAL COLLECTING AND LOADING APPARATUS

Thomas K. Andersen, West Brighton, and Tengel Andersen, Port Richmond, N. Y., assignors to Overhead Loader Corporation, New York, N. Y., a corporation of New York

Application June 17, 1937, Serial No. 148,740

10 Claims. (Cl. 214—131)

This invention relates to an attachment for heavy duty vehicles such as tractors or the like and relates more particularly to a combined material collecting and loading apparatus and detachable ground scraper or bull-dozer.

5 Tractors have heretofore been used in connection with road work excavation and similar operations and attachments of varying constructions have been used. Most of the previous devices 10 were arranged to either dig or collect material or to receive and load material.

It is an object of the present invention to provide a simple and efficient apparatus for collecting and loading material.

15 Another object of the invention is to provide mechanism which may be employed to dig into hard ground and collect the loosened material.

Another object of the invention is to provide 20 an apparatus for conveniently and expeditiously digging, collecting and discharging material.

Another object of the invention is to provide a digging and loading apparatus convertible into a ground scraper controlled by means for actuating said digging and loading apparatus.

25 The present invention, although shown and described for digging, collecting and loading earth, may readily be employed to collect any loose material and load, as in industries where raw material must be transported from one place to another.

30 When used as a ground leveler or digger the present invention has more than ordinary utility since, whereas, other apparatus has heretofore been employed to perform the operation of digging, it was not possible to efficiently load the loosened ground.

In a machine constructed in accordance with 35 the present invention, a scoop or bucket is carried on lever arms or beams having fulcrums at the front or in close proximity to the front of a tractor. The scoop when in operative position is held with its digging edge in position in the rear of the tractor to cut into the ground or pile of material as the tractor is moved, forcing the scoop into the earth or pile so that it collects loosened material.

40 As the tractor moves, a truck may follow it and when the scoop has received a load it is moved in an arc over the tractor and forward until over 45 the truck at which time the scoop may be discharged into the truck.

The pivot point, of the beam which may be termed the carrier for the scoop, is so positioned 50 that relatively great force may be applied for digging and the arrangement is such that when

the scoop is moved to position for discharge, it extends from the tractor to permit a wide range for the disposition in a receptacle such as a truck beneath the loaded scoop.

The invention will be more clearly understood 5 by reference to the following description together with the accompanying drawings, in which

Fig. 1 is a side elevational view of a tractor of the caterpillar type having the present collecting and loading mechanism mounted thereon; 10

Fig. 2 is a plan view of the tractor and mechanism shown in Fig. 1;

Fig. 3 is a front end view of the tractor showing the collecting and loading bucket in dotted lines in an elevated position; 15

Fig. 4 is a detail sectional view of the hoisting drum and gear mechanism for lifting the lever arms;

Fig. 5 is a view taken on line V—V in Fig. 4;

Fig. 6 is a view taken on line VI—VI in Fig. 4; 20

Fig. 7 is a view taken on line VII—VII in Fig. 4;

Fig. 8 is a side elevational view of the digging and loading apparatus having a scraper attached, and

Fig. 9 is a perspective view of a scraper constructed for attachment to the digging and loading apparatus. 25

The present invention may be applied to any suitable design of tractor or power vehicle and as shown in the drawings a tractor 10 of the 30 caterpillar type has been selected.

The caterpillar tractor may include the usual frame 11 having an engine 12 at the forward end and the usual operator's seat 13 at the rear end. The link treads 14 may be driven in the usual 35 manner and controlled by means commonly provided for tractors of this type.

The mechanism embodying the present invention may comprise a sub-frame 15 of any suitable construction and as shown may include a cross-member 16 and lateral or side members 17. Each 40 of these side members may be provided with a bearing plate 20 strengthened by an upright 21, and a supporting cross member 17' (see Fig. 2) attached to the tractor frame 11 at its forward 45 end. The purpose of the cross member 17' is to support the tractor sub-frame 15 rigidly in line with the tractor frame 11 which carries the tractor motor 12, permitting the sub-frame to follow the movement of the tractor frame around 50 the common center of oscillation 25, and without hampering the free and independent oscillation of the tractor tracks, or the movement of the tractor frame upon its springs. Upright members 22, 22' and 23 extend upwardly from each 55

of the side members of the sub-frame 15 and are secured at their upper ends to a cover or roof 24 which is suitably reenforced.

The sub-frame 15 is attached to the track frames adjacent points 25 which are located on each side of the tractor at the common center around which both tracks and the tractor frame may oscillate in a vertical plane independently of each other. A support 25' extending from the body of the tractor also supports the sub-frame 15. Each bearing plate 20 is provided with a pin 18 and has pivotally attached thereto a lever-arm or beam 19. (See Fig. 1.) The pivot pin 18 is disposed intermediate the ends of the tractor and in relatively close relation to the rear end. The beams 19, 19' are of sufficient length to extend beyond either end of the tractor and a digging and collecting implement 27 is pivotally mounted between the free ends 28, 28' of converging beam extensions 19', 19' which latter are offset toward each other to accommodate the implement 27.

The beams 19 are each provided with a fin 30 having a bearing hub 30' and each side member 17 is provided with an extended bearing 30'' to support and effect the operation of a bucket scraper or bull-dozer as will later be described.

The bucket or digging implement 27 which may be termed a scoop is provided with a cutting edge 29 preferably of hardened steel. The scoop is so constructed as to have an open or material receiving mouth 32 and a hinged cover or door 33 held by a suitable latch 34. The latch may be mounted on a cross-support 35 and normally held by a spring 36 to engage the cover. A cable 36' terminating in a grip 37 may be located within reach of the operator when in the seat 13. A pull upon the cable will serve to release the cover to discharge material, as indicated in dotted lines in Fig. 1, as for example, into a truck also indicated in dotted lines.

When the scoop is in position as shown in Fig. 1 the weight of the scoop and the angular relation of the cutting edge thereof results in a digging action when the tractor is moved to cause the digging edge of the scoop to enter the ground or into material to be collected.

It will be noted that in the present preferred embodiment of the invention the digging or collecting is accomplished by a rearward movement of the tractor, the operator turning in his seat to guide the digging operation.

In accordance with the present invention material is collected at one end of the tractor and deposited at the other end and means are therefore provided for swinging the scoop through a vertical plane overhead. This is accomplished by means of a yoke 40 pivoted at 41 to opposite sides of the scoop 27. The yoke has attached thereto, one end of a cable 42 which leads over a guide pulley 43 mounted on the roof 24. The cable extends between pulleys 44 and 45 mounted in close peripheral relation in a bearing block 46. The other end of the cable is fast to a winding drum 47. When the tractor has been operated to cause the scoop to collect material the drum is actuated and the cable wound up to exert a pull on the yoke. This obviously causes the scoop to be lifted and the beams to swing about their pivots 18.

Power for lifting the scoop is obtained from the tractor engine and a clutch lever 48 is provided to engage suitable driving gears and motion translating means, to be later described, which in turn cause a rotation of the drum 47.

When the scoop reaches the vertical or dead center position, as shown in dotted lines in Fig. 1 and is ready to descend on the other end of the tractor, the operator manipulates brake lever 49. Obviously when the scoop is on the point of descending, it is necessary to throw out the clutch and in accordance with the present invention this is accomplished automatically by means to be hereinafter described.

It will be readily understood that while the pull is being exerted upon the cable and the loaded scoop reaches its limit of elevation the cable which travels over pulley 44 during the lift, shifts to pulley 45. The operator then controls the drum by means of the brake lever 49 and eases the loaded scoop to discharge position at which time a pull upon the latch cable 36 releases the cover 33.

The scoop is returned to digging position by throwing in the clutch and releasing the brake. The scoop reaches the vertical position, the clutch is automatically disengaged and the operator applies the brake by moving the brake lever 49 to lower the scoop to such position as may be desired. The tractor is driven in the usual manner and the usual clutch lever is shown and indicated by the reference numeral 51.

The operating mechanism is well known and is therefore not shown or described, it being evident that the present attachment may be applied to any mobile power plant having the flexibility to be driven about and controlled to direct the operation of the scoop. It will be appreciated that the movement of the tractor under the guidance of the operator provides a powerful digging apparatus giving a tremendous amount of power and at the same time may be handled with the simplicity and ease that a workman finds in handling an ordinary shovel to lift material from the ground to a receptacle.

The mechanism for lifting and braking the scoop action is shown in detail in Figs. 4 and 5. The drum 47 is mounted loosely on a shaft 52 journaled in bearings 53 and 54. One end of the shaft 52 is provided with a spur gear 55 in mesh with a gear wheel 56 on a shaft 57 journaled in a bearing in a box 58. The shaft 58 extends through the box and has secured thereto a worm wheel 59 in mesh with a worm 61 on a shaft 62 secured by a coupling 63 to a main drive shaft 64 (see Figs. 1 and 4) of the tractor motor.

As above mentioned, the winding drum 47 is loose on the shaft 52 and is provided at one end with a brake drum 64 and brake band 65. (See Fig. 7.) This brake mechanism is of the usual construction, including a bolt 66 to which one end of the band is attached and a lever 67 having an arm 68 to which the other end of the band is attached. A link 69 connects with a pull rod 71 (see Fig. 1) connected to the brake lever 49.

The clutch mechanism for controlling the rotation of the winding drum (see Figs. 4 and 5), includes a friction collar 72 integral with the winding drum around which is disposed a gripping band 73. The collar is recessed to receive a carrier or rotary member 74 secured to shaft 52. Adjacent to the carrier 74 and loose on shaft 52 is a take-up pulley or drum 75. A friction strap 76 having one end secured at 77 to bearing bracket 54 is arranged to frictionally engage the pulley 75 upon a downward pull upon link 79 attached to the other end of the strap 76. The link 79 is attached to one arm of a bell crank lever 81, the other end of the crank being attached to a

pull rod 82 connecting with the clutch lever 48. (See Fig. 1.)

As above pointed out the carrier 74 is rotatable with the shaft 52 and in order to impart rotary motion to the winding drum 47 connection must be made between the drum and the carrier 74. This is accomplished by bolt 83 at one end of a link 84, the said bolt being threaded and engaged in a threaded aperture in the take-up 10 pulley 75. The other end of the link 84 (see Fig. 6) is pivotally connected at 85 with one end of a lever arm 86 pivoted at 87 on the carrier. The other end of the lever 86 is connected at 88 with one end of the gripping band 13. The 15 other end of the band is attached to one end of a lever 89 pivoted at 91 on the carrier 74. The other end of the lever 89 is provided with a set screw 92 which engages a stop 93 integral with hub 94 of the carrier 74.

20 When the pull rod 82 is actuated to bring the friction strap 76 in contact with the take-up pulley, the said pulley being free on shaft 52 may rotate slightly with the result that the pin 83 causes a thrust upon link 84 by reason of the 25 direction of rotation of shaft 52 to which the carrier 74 is secured. This thrust imparts a rocking movement to the lever 86 with a consequent pull upon the gripping band 13 whereby the winding drum is connected for rotary movement with the shaft 52.

From the above it will be understood that normally the gripping band 13 and the friction strap 76 as well as the take-up pulley 75 all rotate with the carrier 74. The clutch lever 48 is 35 provided with a suitable spring 85' which acts to cause the pull rod 82 to lift the strap 76 so that the actual clutch mechanism is free. When the strap 76 is moved to engage the take-up pulley the initial movement thereof prevents sudden 40 opposition to inertia and provides a smooth and effective means of translating motion from the shaft 52 to the winding drum 47.

When the scoop has been manipulated to receive material and the clutch lever actuated the 45 winding drum takes up on the cable and the beams 19 swing about their pivots. For the purpose of throwing out the clutch after the bucket reaches its upper position, a bell-crank lever 96 (see Figs. 2 and 3) is provided. This 50 lever is pivoted at 97 on the frame of the machine and one arm 98 of the lever is provided with a roller 99 and so positioned that the roller may be moved into the path of travel of a beam 19. The other arm 101 of the lever 96 is engaged 55 by a pin 102 on pull rod 82. When the operator moves the clutch lever 48 to throw in the clutch he holds the clutch lever to keep the clutch in. As the beam 19 reaches its vertical position it 60 engages the roller 99 thereby rocking the bell-crank lever 96 and by reason of the pin 102 the pull rod 82 is actuated causing the operator to release the clutch lever 48 and the clutch no longer operates to connect the shaft 52 with the winding drum. At this time the operator having 65 been given the signal that the scoop is in position to descend, moves the brake lever 49 and controls the downward movement of the scoop. Obviously the return movement of the scoop is 70 accomplished by an actuation of the clutch lever and a movement thereof causes the bell-crank 96 to move the roller 99 into position to be engaged by the beam 19 on its return movement, throwing out the clutch mechanism and giving 75 the operator a definite signal to apply the brake

and control the descent of the scoop for another digging or material collecting operation.

The scoop 21, as will be evident, comprises a novel construction in that it receives material by means of an opening at one side and discharges through the top upon an opening of the door 33. This novel form of scoop is particularly adapted to the overhead swing which causes the material to settle against the door and as the scoop reaches the discharge position and the door is unlatched the weight of the material effects an immediate opening of the door and an expeditious discharge.

The present scoop construction greatly simplifies the apparatus since it avoids a swinging 15 or pivoted type scoop with the attending added parts and maintenance due to wear.

Although the present invention provides an efficient and practical apparatus for lifting and loading material the mechanism for lifting the scoop is particularly effective when used in combination with a scraper or what is termed a bulldozer or snow plow.

As shown in Figs. 8 and 9 a scraper plough 103 of any suitable type may be applied to the front 25 end of the tractor. The selected form of scraper as shown includes a plate 104 with reinforcing gusset plates 105 and arms 106. Each arm is pivotally connected by a pin to an extended bearing 30'. The arms 106 hold the scraper 30 with the nose 109 thereof positioned to make close contact with the ground. Ordinarily a scraper of this character is in a sense uncontrollable. That is, no means are provided to conveniently lift the scraper or to exert a force to 35 cause a deeper cut.

In accordance with the present invention this disadvantage has been removed since the beams 19 manipulated by the clutch and brake give 40 entire control of the scraper, plough, or other implement.

An actuation of the scraper is attained by means of links 110, each link having one end pivoted at 112 to plate 104 and the other end pivotally connected at 113 to an extended bearing 30'.

The operation of the scoop has been fully explained above and it will therefore be readily understood that by causing the beams 19 to ascend the nose of the scraper will be forced into the 50 ground. When the beams are permitted to descend the scraper will be lifted. Thus by manipulating the clutch and brake the scraper is under the full control of the operator.

The present invention not only provides a 55 simple and effective apparatus for collecting, lifting and discharging material, but the same mechanism serves to operate a ground scraper snow plough with equal effectiveness thus making it possible to provide two of the most important 60 implements capable of being operated at different times, but utilizing the same operating or motion transmitting elements.

Although a preferred embodiment of the invention is shown and described herein, it is to 65 be understood that modifications may be made therein without departing from the spirit and scope of the appended claims.

What is claimed is:

1. A material collecting and discharging apparatus comprising a lever member, a pivot at one end of said member for vertical swinging movement through and past a vertical plane through the pivot axis, two guide pulleys arranged in close spaced relation, one on each side of said vertical 70 75 78

plane, a cable extending between said pulleys, means for exerting a pull on said cable for hoisting said member through the upswing portion of its travel and means for automatically rendering said last mentioned means inoperative when said member passes through said vertical plane to allow paying out of the cable during the downswing portion of the travel of said member.

2. A material collecting and discharging apparatus comprising a lever member, a pivot at one end of said member for vertical swinging movement through and past a vertical plane through the pivot axis, two guide pulleys arranged in close spaced relation, one on each side of said vertical plane, a cable extending between said pulleys, means for exerting a pull on said cable for hoisting said member through the upswing portion of its travel and means for automatically rendering said last mentioned means inoperative when said member passes through said vertical plane to allow paying out of the cable during the downswing portion of the travel of said member, and means for arresting the movement of said member during the downswing portion of its travel.

3. In combination with a self propelling tractive vehicle, a pair of supporting arms pivoted adjacent the sides of said vehicle, a receptacle mounted at the outer ends of said arms, said arms being of a shape and length to carry said receptacle in a vertical arc from loading position at one end of the vehicle along its fore and aft center line and past the pivot points of said arms to dumping position, power lifting means for revolving said receptacle and arms from positions on either side of the vertical to an approximately vertical position, manual means for causing the application of said lifting power to said receptacle and for discontinuing such application, manual means for optionally arresting the travel of said receptacle at any point, the side of said receptacle farthest from the pivot points of its arms being open, and an upper side of said receptacle when in digging position being equipped with a hinged and latched cover, manual means for optionally releasing the cover latch at any point in the travel of the receptacle so that when the receptacle has become partially or wholly inverted by the revolution of its arms its load may be dumped, the hinge line of said cover being located at the edge of the cover farthest from the pivot points of the arms so that gravity will tend to maintain the cover when open in position to be closed by its own momentum as the movement of the receptacle is arrested on its descent towards loading position and will assist in such closing when the receptacle approaches loading position and so that when the load is being dumped said cover will be in position to and will tend to reduce the throwing of the load away from the vehicle resulting from stopping the motion of the receptacle.

4. The combination of claim 3, the cover latch releasing means comprising an actuating device under control of the operator and operative connections between the latch and the said actuating device, said operative connections passing through a point sufficiently near the pivot center of the receptacle arms to make the operator's movement in releasing the latch substantially uniform at all points along the travel of the receptacle.

5. In combination with a self propelling tractive vehicle, a pair of supporting arms pivoted adjacent the sides of said vehicle, a digging receptacle mounted at the outer ends of said arms

designed to dig and load itself at the rear of the vehicle, said arms being of a shape and length to carry the receptacle in a vertical arc from loading position at the rear of the vehicle along its fore and aft centre line past the pivot points of said arms to a forward dumping position, power means for revolving the receptacle and arms from either side of the vertical to an approximately vertical position, manual control means for causing and discontinuing the application of revolving power and for optionally arresting the movement of the receptacle at any point, said control means being located near enough to the rear of the vehicle to permit the operator when using said control means to have unobstructed vision of the receptacle when in low loading position.

6. In combination with a self-propelling tractive vehicle, a pair of supporting arms pivoted adjacent the sides of said vehicle, a receptacle mounted at the outer ends of said arms, said arms being of a shape and length to carry the receptacle in a vertical arc from loading position at the rear end of the vehicle along its fore and aft center line past the pivot points of said arms to a forward dumping position, means for converting the motor power of the vehicle into power to revolve the receptacle and arms to an approximately vertical position, said converting means being mounted ahead of the vehicle to act as a counterbalance against the vehicle tipping up in front when the receptacle is breaking out its load at the rear of the same, means connecting said power converting means with the motor of the vehicle and means for optionally arresting the movement of said receptacle at any point.

7. In combination with a self propelling tractive vehicle, a pair of supporting arms pivoted adjacent the sides of said vehicle, a receptacle mounted at the outer ends of said arms for loading at one end of the vehicle, said arms being of a shape and length to carry said receptacle in a vertical arc from the loading end of the vehicle along its fore and aft centre line past the pivot points of said arms to dumping position, a power-operated cable for revolving said receptacle and arms from either side of the vertical to an approximately vertical position, a protective roof over the vehicle, cable guiding means mounted on said roof substantially over the pivots for the arms, said roof being designed to support the entire strain of lifting the receptacle at one end of its arc and of stopping its descent at the other end, and means adjacent the loading end of said roof for protecting the cable against chafing on same when the receptacle descends below its level to load.

8. In combination with a tractor, a pair of supporting arms pivoted adjacent the sides of said tractor, a receptacle mounted at the outer ends of said arms, said arms being of a shape and length to carry said receptacle in a vertical arc from loading position at one end of the tractor along its fore and aft center line past the pivot points of said arms to dumping position, means for converting the motor power of the tractor into power to revolve the receptacle and arms from either side of the vertical to an approximate vertical position, power-transmitting means operated thereby, a protective roof above the tractor, and an independent sub-frame providing a support for the roof and for said power converting means and so fastened to the tractor that at all times it keeps said power-converting means in line with the tractor motor while still

permitting free spring movement of the tractor and the independent oscillation of its tracks.

9. In combination with a self-propelling tractive vehicle, a pair of supporting arms pivoted adjacent the sides of said vehicle, a receptacle mounted at the outer ends of said arms, said arms being of a shape and length to carry said receptacle in a vertical arc from loading position at one end of the vehicle along its fore and aft center line and past the pivot points of said arms to dumping position, power lifting means for revolving said receptacle and arms from positions on either side of the vertical to an approximately vertical position, manual means for causing the application of said lifting power to said receptacle and for discontinuing such application, manual means for optionally arresting the travel of said receptacle at any point, and means for automatically discontinuing the application of lifting power to said receptacle as it approaches its vertical position from either direction and for releasing it from any control by said lifting power so that it may be free to pass the vertical by momentum and drop by gravity.

10. In combination with a self-propelling tractive vehicle, a pair of supporting arms pivoted adjacent the sides of said vehicle, a receptacle mounted at the outer ends of said arms disposed to dig and load itself at the rear of the vehicle, said arms being of a shape and length to carry the receptacle in a vertical arc from loading position at one end of the vehicle along its fore and aft center line past the pivot points of said arms to dumping position, means for converting the motor power of the vehicle into power to revolve the receptacle and arms to an approximately vertical position, means connecting said power converting means with the front end of the motor shaft of the vehicle so that the vehicle may move itself, its gears be shifted, and its direction of travel be reversed without interrupting said lift, means for returning the receptacle to loading position, and means for optionally arresting the movement of the receptacle at any point.

THOMAS K. ANDERSEN.
TENGEL ANDERSEN.
